UNITED STATES PATENT OFFICE

2,641,852

SHOE AND HEEL ATTACHED THERETO

James F. Leahy, Beverly, and George F. C. Burke,
Fairhaven, Mass., assignors to United Shoe
Machinery Corporation, Flemington, N. J., a
corporation of New Jersey

Application November 30, 1950, Serial No. 198,400

2 Claims. (Cl. 36—24.5)

1

This invention relates to shoes and to heels which may be advantageously attached to said shoes by practicing the method disclosed in United States Letters Patent No. 2,607,061, granted August 19, 1952, on an application filed in the names of Leahy et al.

As disclosed in said patent it has been proposed to form in the heel seat of a shoe and the attaching face of a heel, which is to be attached to the shoe, anchoring cavities, respectively, and after the heel has been positioned upon and clamped against the heel seat of the shoe, to inject viscous thermoplastic resin into the anchoring cavities thereby filling with the resin said cavities as well as any voids formed between the heel seat of the shoe and the attaching face of the heel. The heel is held clamped against the heel seat of the shoe until the thermoplastic resin hardens and shrinks and thus becomes a solid fastening serving effectively to secure the heel permanently to the shoe.

The present invention consists in an improved shoe having a heel provided with a passage which extends from the breast of the heel to the anchoring cavity in the attaching face of the heel and through which resin is supplied to attach the heel to the shoe in accordance with the method disclosed in said Patent No. 2,607,061, reference being had to the accompanying drawings illustrating embodiments of the invention which is fully disclosed in the following description and claims.

In the drawings,

Fig. 1 is an exploded view showing in perspective a heel seat of a shoe and a heel which is to be attached to the shoe by thermoplastic resin;

Fig. 2 is a longitudinal median section through the heel seat of the shoe and the heel attached to the shoe;

Fig. 3 is a view on line III—III of Fig. 2; and

Fig. 4 is a longitudinal median section through the upper forward end portion of a modified heel attached to a shoe.

The present invention is illustrated with reference to a heel 20 and a shoe 22 to which said heel is attached by practicing the method disclosed in the above-mentioned Patent No. 2,607,061. As above explained, in order permanently to attach heels 20 to shoes 22 it has been proposed to form in the heel seat 24 (Fig. 1) of the shoe an undercut recess 26 (Figs. 1 and 2) which in its entirety may be referred to as an anchoring cavity, the heel having formed in its attaching face 28 (Fig. 1) a pair of cross

2

slots 30 which may be described as anchoring cavities and the general planes of which are inclined to a plane of a rim 32 of the attaching face of the heel. The illustrative heel 20 has applied to it a one-piece cover 34 which is wrapped about and secured to the rear and side faces of the heel and opposite forwardly projecting margins of which are secured to the uncovered breast 36 (Figs. 1 and 3) of the heel and have their margins tucked side by side in a heightwise median slot 38 (Figs. 2 and 3) formed in the breast of the heel. The upper margin of the cover 34 is inturned upon and secured to the attaching face 28 of the heel and the lower margin of the cover is inturned upon and secured to a top lift receiving face 40 of the heel to which face a top lift 42 is nailed. In order to strengthen the heel 20 it is provided with a metal dowel 44 extending heightwise of the heel along its lower median portion.

In order, after the heel 20 has been positioned upon and forced with heavy pressure against the heel seat 24 of the shoe, to inject viscous thermoplastic resin into the cavities 26, 30 in the heel seat of the shoe and in the heel as well as into voids existing between the heel seat of the shoe and the attaching face of the heel, heels have heretofore been provided with passages (not shown) which extend heightwise of the heel between the top lift receiving face 40 of the heel and intersecting portions of the cross slots 30. In high heels such passages are necessarily long and because of the small horizontal sectional area of the heel are usually of limited sectional area. Accordingly resin forced through the passages tends to cool and harden and unless forced under high pressure, which is undesirable, said hardened resin tends to restrict flow of viscous resin through said passages. Moreover, a passage extending from the top lift receiving face of the heel to intersecting portions of the slots 30 in the attaching face 24 of the heel requires to fill it a substantial amount of resin which is expensive and considerably heavier than wood and to leave substantial lengths of the lower ends of such passages unfilled weakens the heel. Furthermore, high heels such as above referred to have reinforcing dowels driven into them and accordingly it is impracticable to form said passages in such heels.

With the above considerations in view the present heel 20 has a passage 48 (Figs. 1 and 2) extending from the intersecting portions of the cross slots 30 to the upper central portion of the breast 36 of the heel, said passage extending

through the cover receiving slot 38 formed in the breast of the heel and through the cover 34 applied to said breast.

A covered heel 20A (Fig. 4) of the general type shown in Fig. 2 but not having a cover receiving slot 38 has a resin receiving passage 48A which is similar to the passage 48 but extends without interruption to the covered breast 36A of the heel. It is the practice to withdraw the resin injector (not shown) from the passage 48 or 48A as said passage becomes filled and before the resin has filled the passage to a point adjacent to the outer or heel breast end of said passage 48A (Fig. 4) or to the heel cover receiving slot 38 (Fig. 2), a valve (not shown) is operated to shut off the supply of resin from the injector which is then withdrawn from said passage.

In order that the passage 48 and a registering hole in the cover 34 shall not be visible in the finished shoe it is customary for the operator before the resin 46 hardens or sets to insert over the breast end of the passage 48 a rigid cap or button 50 an outer face of which has a desired design and an inner face of which has a flange 52 which extends approximately to the bottom of and fits snugly in the cover receiving slot 38 and to which is attached at least one metal strip 54 which may be considered as part of said cap and when the cap rests against the covered breast of the heel extends into the then semi-hardened viscous resin 46.

Instead of providing the cap 50 a modified cap 56 (Fig. 4) may be provided, said cap having an outer face of a desired design. An inner face of the cap 56 has secured to it a plurality of resilient barbed fingers 58 which are spring-pressed against the wall of the outer portion of the passage 48A to hold the cap firmly in place against the covered breast 36A of the heel 20A.

Having thus described our invention, what we

claim as new and desire to secure by Letters Patent of the United States is:

1. A shoe having an anchoring cavity in its heel seat and having a heel an attaching face of which is provided with an anchoring cavity and which has a passage extending to its breast from said cavity, said cavities, said passage and voids formed between the heel seat of the shoe and the attaching face of the heel being substantially filled with hardened thermoplastic resin in serving permanently to secure the heel to the shoe, a rigid cap which engages the breast of the heel and overlies a heel breast end of the passage, and an extension on said cap anchored in the resin in said passage.

2. A shoe having an anchoring cavity in its heel seat and having a heel an attaching face of which is provided with an anchoring cavity and which has formed in its breast a heightwise extending medial slot and has a passage extending from its cavity through said slot to the breast of the heel, said cavities, said passage and voids formed between the heel seat of the shoe and the attaching face of the heel being substantially filled with hardened thermoplastic resin serving permanently to secure the heel to the shoe, a rigid cap which engages the breast of the heel and having a flange which fits in the slot in the breast of the heel, and a metal strip on said cap anchored in the resin in said passage.

JAMES F. LEAHY.

GEORGE F. C. BURKE.
